FIG. 9

FIG. 10

FIG. 11

FIG. 12

FIG. 1 is a perspective view of a toy lounge seat showing my new design;

FIG. 2 is a front elevation view of the design of FIG. 1;

FIG. 3 is a rear elevation view of the design;

FIG. 4 is a top plan view of the design;

FIG. 5 is a bottom view of the design;

FIG. 6 is a right end view.

The left end view is a mirror image of FIG. 6.

FIG. 7 is a perspective view of a toy lounge seat showing a modified form of my new design;

FIG. 8 is a front elevation view of the design of FIG. 7;

FIG. 9 is a rear elevation view of the design;

FIG. 10 is a top plan view of the design;

FIG. 11 is a right end view; and

FIG. 12 is a bottom view of the design.

The left end view is a mirror image of FIG. 11.

This case is a continuation of my two earlier applications Ser. Nos. 305,903 and 305,907, both filed Nov. 13, 1972 and now abandoned.

I claim:

The ornamental design for a toy lounge seat or similar article, as shown and described.
